(54) **THRASHING, & CORN SHELLING
MACHINE**

(76) Inventor: **David Knauer**

This is to certify that I, David Barnes, of Chester County, State of Pennsylvania, have made improvements to or the useful arts, being a machine for separating all kinds of grain and seeds from the straw and husk, and for cleaning the same, called Barnes' Threshing & Corn-shelling machine.

I, David Barnes, of Chester County, State of Pennsylvania, do hereby declare that I have invented a machine for separating all kinds of grain and seeds from the straw and husk, and for cleaning the same, also called Barnes' Threshing Cleaning & Corn-shelling machine, which is described and fully referred to in the accompanying drawings.

The machine for separating seed and grain from the straw and husk, marked A, consists of a revolving cylinder of beater, and a stationary box, with an inclined vibrating screen for separating the straw from the grain, and a fan for drawing air through the screen.

The strong plates B, are made of wood and either iron or entirely of iron, and are formed so as to overlap, their ends being fixed in a circular bed D. This cylinder turns on an axle E, being on a pair of friction wheels F, upon a frame, on either end of this axle is a wheel G, for driving the cylinder by a band H passing round the pulley I. The bed K.

object placed above the former, in the centre of which is fixed a cog-wheel a working into the rounds of the above-mentioned level wheels and which gives motion to them. This cog-wheel is cast cold, having points or projections cast on each side, which work sufficiently near the projections on the two level wheels, and by which the latter is rubbed out or relieved. The end of a connecting rod introduced by the hand into the openings, by which it is conducted to the level wheels to be rubbed out, there are two springs b , one over each level wheel for holding down the ears of corn, and connected with the cover.

Operation of the grain threshing machine.

The grain to be threshed is placed upon an inclined board d , motion is given to the main level wheel c of pulley by any convenient means; the grain and straw are drawn in by the revolving beaters, by means of which and the bed, the grain is separated from the straw; the grain and straw then fall on the inclined vibrating board, the grain falling through between the bars on to the riddle, and the straw thrown out at the end; it then falls upon another inclined plane e , placed below in a recessed position, where it is subjected to a winnowing machine which thoroughly cleans it. There is another inclined board f immediately behind the one marked e , which catches the grain that escapes it. The grain is then received by an inclined spout or shot, going across the bottom of the machine at the lower end of the inclined plane e , which carries the grain out at the side of the machine to the rear.

Operation of the corn hulling machine.
